UNITED STATES PATENT OFFICE.

HERMAN Z. CUTLER, OF CAMDEN, NEW JERSEY.

MEANS FOR INCREASING THE STRENGTH OF SHEET-METAL ARTICLES.

Application filed November 23, 1923. Serial No. 676,513.

My invention relates to means for making articles formed into various shapes out of sheet metal strong, rigid and relatively inflexible, and more particularly relates to 5 means for imparting great strength and rigidity to such articles as fenders, mud-guards and running-boards of automobiles.

In the manufacture of sheet metal articles, such as fenders, mud-guards and running-boards of automobiles, it has been common practice heretofore to bend the free edges of the article over and around a wire or rod to make the completed article stiffer and more inflexible. But such rods or wires are 10 always of relatively small diameter and fail to impart to the article sufficient strength or rigidity to prevent it from bending or crumpling when the car on which the article is used collides even gently with a rigid object. 15 Whenever a mud-guard or fender of the kind above described strikes against a wall of a garage or a side of a door of a garage, for example, the fender will be bent and crumpled and will absolutely fail to prevent 20 the body of the car from being struck or injured.

It is the object of my invention to so increase the strength and rigidity of sheet metal articles such as are above referred to 25 that the fender or running-board will not bend or crumple in the case of a slight collision and which will be so strong and rigid that it substantially forms a bumper which will protect the car in the case of a violent 30 or more serious collision.

A further object of my invention is to provide reinforcing means on the free edges of fenders and running-boards of such a nature as to protect the car in such a way as 35 to provide a convenient mode of attaching the same to the chassis or body of the car.

A further object of my invention is to provide the free edges of mud-guards and fenders with stiff tubes made of sheet metal rigidly secured to such free edges and when desired filled with concrete, plaster of Paris or any other suitable cementitious material.

A further object of my invention is to provide the free edges or margins of the running-boards and fenders with a strong protecting tube rigidly attached thereto in such a manner as to improve the appearance of the article on which the tube is secured.

Other objects of my invention will appear in the specification and claims below.

The form of my invention as hereinafter

described, comprises a running-board disposed between and connecting the front and rear fenders, to form an integral guard structure, each having their free edges protected by substantially cylindrical reinforcements whose edge flanges overlap the margins of the guard members and afford a continuous reinforcement and protector for the free edge of said guard structure; said cylindrical reinforcements affording tubular sockets arranged to receive the studs of supporting brackets or connecting dowels.

My invention also includes all of the various novel features of construction and arrangement as hereinafter more definitely specified.

In the accompanying drawings:

Fig. 1 is a perspective view of a motor vehicle having a running-board and fenders comprising the integral guard structure, and conveniently embodying my invention;

Fig. 2 is an enlarged fragmentary perspective view of the guard structure shown in Fig. 1;

Fig. 3 is a fragmentary detailed perspective view showing the adjacent ends of the forward fender and running-boards slightly separated for convenience of illustration;

Fig. 4 is a fragmentary transverse sectional view in perspective showing in detail the means of attachment of the preferred embodiment of the reinforcing protector as applied to the guard structure;

Fig. 5 is a front elevational view of the forward fender showing the means of its attachment to the chassis;

Fig. 6 is a transverse sectional elevational view showing the means of its attachment to the chassis;

Fig. 7 is a fragmentary sectional elevational view showing the dowel connecting the reinforcing protector of the running-board and rear fender;

Fig. 8 is a fragmentary plan view showing the front fender, running-board and chassis.

Fig. 9 is a side elevational view showing the structure depicted in Fig. 8; and

Figs. 10, 11, 12, 13 and 14 are fragmentary transverse views in perspective, showing various modifications of the structure illustrated in Fig. 4.

In said figures the motor vehicle comprises the body 1, wheels 2 and 3 and the chassis 5 from which extends the bracket 6 supporting the front wheel guard or fender 7; the

brackets 8 supporting the running-board 9; and the bracket 10 supporting the rear wheel guard or fender 11.

As shown in the drawings the front and rear fenders 7 and 11, and the running board 9 are preferably formed of sheet metal, the free edges of which are provided with a protective reinforcement, which, as best shown in Fig. 4, may be formed of relatively stiff sheet metal tubing 13, shaped to conform to the shape of the edge of the fenders and running-board and having longitudinally extending fins or flanges 15 and 16 formed by the plane margins of said sheet metal reinforcement; and adapted to underlap the outer free margin 17 of the running-board 9 and to serve, not only to provide convenient means by which the tubing may be secured to said running-board (as by spot welding 19 or any other suitable means) but also to provide strength and rigidity to the whole structure. The web forming the tubular protector, may preferably be folded in a variety of ways to form a re-entrant longitudinally extended slot, pocket or recess 20, into which the downwardly dipped offset extreme outer edge margin 21 interlocks.

It may be here noted that although I have described the protective reinforcement shown in Fig. 4, as applied to the running-board 9, it is to be understood that the same structure applies to the front and rear fenders as well, the tubing being bent to conform to the shape of the free edges thereof.

The inner edge margins of the forward fenders 7, the running-board 9, and the rear fender 11 are turned normal thereto and provide the flanges 23, 24 and 25 respectively which facilitate the fitting of said parts to the chassis 5, and the adjacent ends of the fender 7 and running board 9 are provided with depending flanges 26 and 27 respectively, which have alined bolt holes 28 and 29 through which bolts or rivets may be extended to secure said parts together in integral relation, to form the guard structure. Similarly, the adjacent ends of the running-board 9 and the fender 11 are provided with depending flanges 31 and 32 which have the alined bolt holes 33 and 34 through which bolts or rivets may extend.

The adjacent ends of the protective reinforcement of the forward fender 7 and running board 9 conveniently provide tubular sockets 36 and 37 for the reception of the dowel pin 38 shown in Fig. 3, and the adjacent ends of said protective reinforcement of the rear fender 11 and running board 9 conveniently provide tubular sockets 40 and 41 for the reception of the dowel pin 42, which is angular, see Fig. 7, owing to the fact that the rear fender 11 joins the running-board 9 in substantially normal relation, as best shown in Figs. 1 and 2, and

the cylindrical portion of said protector may be mitered to fit as shown in said figures.

The pins 38 and 42 may be rigidly secured to one or both of the sockets in which each pin is fitted by spot welding or brazing. 70

As best shown in Figs. 8 and 9 the forward terminal of the tubular portion of the protector 13 of the forward fender, affords a socket 43 arranged to receive the rigid stud 44 of the supporting bracket 6, and as shown in Figs. 1 and 6 the rearward terminal of said protector of the rear fender 11 affords a socket 45 arranged to receive the stud 46 of the fender supporting bracket 10. These studs 44 and 46 may be spot 80 welded or brazed in the ends of the tubing 13.

In the form of my invention as shown in Fig. 10 the reinforcing protector is formed of sheet metal shaped into a tube 50 having its margin 51 folded to form a longitudinal pocket 52 for the reception of the downwardly offset outwardly extended extreme edge margin 53 of the fender or running-board structure 54, and extended inwardly beneath said fender or running-board and secured thereto, preferably by spot welding 55, to provide reinforcement therefor.

In the form of my invention as shown in Fig. 11 the reinforcing protector is formed of sheet metal shaped into a tube 60 having one of its margins 61 folded upwardly and outwardly to interlock with the downwardly and inwardly folded edge margin 62 of the fender or running-board structure 63, while the other margin 64 of said protector is extended inwardly beneath said fender or running board and secured thereto by spot welding 65.

In the form of my invention as shown in Fig. 12 the reinforcement protector is formed of sheet metal shaped into an open sided tube 70 and through the slot 71 formed by the open side, the downwardly curled edge margin 72 of the guard structure 73 extends. Said curled edge margin 72 may be embedded in any suitable filling, such as cement or concrete 74 which may fill said tube and rigidly secure said guard and protector together.

In the form of my invention as shown in Fig. 13, the reinforcement protector is formed of sheet metal shaped into a tube 80 having its upper margin 81 folded upwardly and outwardly in interlocked relation with the downwardly and inwardly folded margin 82 of the guard structure 83, while the lower margin abuts against the lower surface of the interlocking fold being secured by the spot welding 84.

In the form of my invention as shown in Fig. 14 the protector is formed into a tube 90 having its upper margin 91 extended inwardly and folded downwardly and outwardly in interlocked relation with the downwardly offset, upwardly and inwardly 130

folded edge margin 92 of the guard structure 93 and secured in interlocked relation by spot welding 94, while the lower edge margin 95 has its edge abutted against the 5 under surface of the upper margin, forward of said folded interlock.

As shown in Figs. 10 to 14 inclusive, the tubular portion of the protector is preferably filled with any suitable cement, such as 10 concrete, Portland cement or plaster of Paris 74 which serves to greatly strengthen and stiffen the fender and running-board structure and substantially forms a protective bumper on the sides of the car and at the 15 ends of the fenders.

In my invention the forward and rearward fenders and interposed running-board may be readily assembled to form a rigid 20 unitary structure having a substantially continuous tubing at the edge thereof which not only strengthens and stiffens the structure, but affords convenient means for attaching the fenders and running-board to the chassis, and to each other. The marginal tubing 25 also imparts a pleasing finish to the fenders.

In making my improved fenders and running-board, the free offset edge of the member is inserted into the longitudinal slot of 30 the tubing and the laterally extending flange or margin of the tubing is rigidly secured to the fender or running-board by rivets or by lap welding. Portland cement, plaster of Paris, concrete or any other plastic cement may then be forced into the tube from one 35 end thereof until the entire tube is filled with the cement. Then a pin or rod may be inserted in the ends of the tubing which are adapted to be secured to the brackets 6 and 10 to form the socket for the reception of 40 the free ends of the brackets and similarly, the dowel pins 48 and 40 may be inserted in one end of the fenders respectively. Similarly, the tubing is secured to the free edge 45 of the running-board and the cement or plaster of Paris is forced therein.

The parts may then be assembled and placed on the chassis in the manner above described and if desired the brackets 6 and 10 and the dowel pins 38 and 42 may be spot 50 welded to the tubing.

I do not desire to limit my invention to the precise details of construction and arrangement as herein set forth, as it is obvious that various modifications may be made therein 55 without departing from the essential features of my invention as defined in the appended claims.

Having thus described my invention, I claim:

1. In a device of the class described the combination with a guard structure, of a protector for the edge thereof, formed of sheet material shaped to form a rigid metal reinforcing tube having a longitudinally disposed portion folded to provide a pocket to 60 receive the free edge of said guard structure and extended to underlap said guard structure and rigidly secured thereto.
2. A continuous rigid protector for the free edge of the fenders and running-board 70 of a vehicle, comprising a stiff sheet-metal tube having its wall folded to form a re-entrant longitudinally extending recess arranged to interlock with said free edge.
3. A continuous rigid protector for the 75 free edge of the fenders and running-board of a vehicle, comprising a tube having its wall folded to provide a re-entrant pocket in which said free edge is interlocked, said pocket extending over the entire free edge of 80 said fenders and running-board to reinforce the same.
4. A continuous rigid protector for the free edge of the fenders and running-board, constituting the guard structure of a vehicle, comprising a tube having formed in 85 its wall a re-entrant recess extending the full length of said tube and into which the entire free margin of said guard structure is tightly fitted, said tube being operative to 90 make rigid the entire guard structure.
5. A continuous rigid sheet metal protector for the free edge of the fender and running-board, constituting the guard structure of a vehicle, comprising a hollow bar having 95 its wall folded to embrace the free margin of the guard structure and having a longitudinal fin extending in underlapped relation to said guard structure and rigidly secured to said guard structure to afford reinforcement therefor. 100
6. In a device of the class described, the combination with the fenders and running-board constituting the guard structure of a vehicle and guard supporting brackets 105 therefor, of a tubular member shaped from sheet-metal and conforming to the shape of the free edge of said structure and affording terminal sockets arranged to receive said brackets and having a recess in which said 110 free edge of said guard structure is rigidly secured.
7. In a device of the class described, the combination with a front fender, a rear fender and a running board comprising the 115 guard structure of a vehicle, of sheet metal tubes shaped longitudinally to conform to the free edges of said fenders and board respectively and rigidly secured thereto, guard supporting brackets respectively adjacent the front end of the front fender and the rear end of the rear fender, said brackets fitting respectively into the adjacent ends of said tube, and dowel pins tightly fitted into 120 said tubes between the running board and the fenders to join the adjacent ends of said tubes and to provide a rigid protector for said guard structure. 125
8. A rigid protector for the free turned under edge of a guard structure of a ve- 130

hicle, comprising a sheet metal tube providing a hollow bar having a longitudinal fin or web and folded over and united to the edge of said guard structure in a lock seam joint.

9. A device of the class described, comprising a rigid protector for the free edge of the guard structure of a vehicle, said rigid protector comprising a sheet metal tube shaped longitudinally to conform to the shape of the free edge of the guard structure and provided with a longitudinally extending fold forming a recess into which the free edge of the said guard structure projects and snugly fits, and means to rigidly secure said tube to said guard structure.

10. A rigid protector for the free edge of the guard structure of a vehicle, comprising a sheet metal tube shaped longitudinally to conform to the shape of the free edge of said guard structure, and having a longitudinally extending recess therein into which the free edge of said guard structure extends and is enclosed, said tube being filled with cement.

11. In a device of the class described, the combination with a guard structure, of a protector for the edge thereof, formed of metallic sheet material, shaped into a rigid reinforcing tube having a longitudinally

disposed portion thereof folded to provide a pocket to receive the free edge of said guard structure and extended to underlap said guard structure and rigidly secured thereto, said tube being filled with cement.

12. In a device of the class described, the combination with a guard structure of an automobile, a continuous rigid protector for the free edge of said guard structure, comprising a metallic tube having its wall folded to provide a reentrant pocket into which the free edge of said guard structure is inserted and interlocked, said pocket substantially extending over the entire free edge of said guard structure to reinforce the same and rigidly secured thereto, said tube being filled with cement.

13. In a device of the class described, the combination with a fender and running-board constituting the guard structure of a vehicle and guard supporting brackets therefor, of a tube shaped from sheet metal and conforming longitudinally to the shape of the free edge of said guard structure and having a recess into which the free edge of said guard structure projects, said tube being filled with cement and spot-welded to said guard structure.

In witness whereof, I have hereunto set my hand this 21st day of November, 1923.

HERMAN Z. CUTLER.
